6 Claims

ABSTRACT OF THE DISCLOSURE

Input signal (read from a magnetic medium) is a self-clocking signal in which a transition occurs in the middle of a bit cell representing a "1" and a transition occurs between two successive bit cells representing "0's." A timing extraction circuit generates a first timing wave having a pulse during the first half of each bit cell, and a second timing wave having a pulse during the second half of each bit cell. The timing waves are used to effect a comparison of the first and second halves of each input signal bit cell. If different, output NRZ coded bit is a "1," and if they are the same, output NRZ coded bit is a "0." NRZ output signal is suitable for application to a shift register.

This invention relates to digital information code converters, and has for its object the provision of an improved converter for translating a self-clocking input information signal, in which a transition occurs in the middle of a bit cell representing a "1" and a transition occurs between bit cells representing two successive "0's" to a simple non-return-to-zero (NRZ) output signal containing the same digital information.

While not limited thereto, the invention is particularly useful in magnetic recording and reproducing systems which employ the above-described self-clocking signal for the recording of information on a magnetic medium with a relatively high packing density. After the self-clocking high-density information signal is read from the magnetic medium, the converter of the invention is useful for converting the reproduced signal to a simple NRZ signal and a clock pulse wave suitable for application to the respective signal and shift inputs of a conventional shift register.

In accordance with an example of the invention there is provided a code converter receptive to a self-clocking input information signal in which a transition occurs in the middle of a bit cell representing a "1" and a transition occurs between bit cells representing two successive "0's." Timing pulse waves are generated under synchronizing control of the input signal. A first timing wave has a pulse occurring during the first half of each input bit cell, and a second timing wave has a pulse occurring during the second half of each input bit cell. A first gate means is enabled by pulses of the first timing wave and the input signal to set and reset a first flip-flop and thereby produce a delayed input signal. A second gate means is enabled by pulses of the second timing wave to set a second flip-flop when the input signal and delayed input signal are different (indicating a "1" transition), and to reset the flip-flop when the input signal and delayed input signal are the same (indicating a "0" bit). The output of the second flip-flop is a simple non-return-to-zero signal containing the information of the input signal.

In the drawing:

FIG. 1 is a chart of voltage waveforms showing an input information signal in a self-clocking high-density code, intermediate voltage waveforms, and an output information signal in the simple NRZ code; and

FIG. 2 is a diagram of a code converter constructed according to the teachings of the invention to provide the code conversion illustrated by waveforms in FIG. 1.

2

Referring now in greater detail to the drawing, FIG. 1a shows the waveform of a self-clocking high density input information signal in which a transition occurs in the middle of a bit cell representing a "1" and a transition occurs between bit cells representing two successive "0's." The input information signal of FIG. 1a conveys the illustrative binary information 000010111. The first four "0's" are illustrative of an all "0's" preamble for a message beginning with the information 10111. An all "0's" preamble is employed to insure correct phasing of the timing pulse waves extracted from the input signal. FIG. 1v shows the output signal in the simple NRZ code suitable for application to the signal input of a conventional shift register. FIG. 1g shows a clock output wave suitable for application to the shift input of the shift register.

Reference is now made to the upper portion of FIG. 2 for a description of the portion of the converter which extracts timing pulse waves from the input signal. The signal input terminal 10 in FIG. 2 receives the input signal wave shown in FIG. 1a. Inverter I₁ produces an inverted input signal shown in FIG. 1b. A delay unit D₁ produces an inverted and delayed input signal as shown in FIG. 1c. A gate G₁ receives the input signal of FIG. 1a and the inverted and delayed input signal of FIG. 1c and produces at its output a wave as shown in FIG. 1d. Gate G₁, and all other similarly represented gates to be described, are conventional "and" gates. Other types of gates may, of course, be employed provided that appropriate attention is given to the polarities of the signals involved and the basic functions performed by the gates.

Inverter I₂ inverts the input signal of FIG. 1a to produce the inverter signal of FIG. 1b. An inverter I₃ reinverts the input signal, and a delay unit D₂ produces a delayed input as shown in FIG. 1e. The waves of FIGS. 1e and 1b are applied to a gate G₂ to provide an output wave as shown in FIG. 1f. The waves of FIGS. 1d and 1f are combined to result in the wave shown in FIG. 1g.

The wave of FIG. 1g is inverted by an inverter I₄ to produce a wave shown in FIG. 1h, and is delayed in a delay unit D₃ to produce a wave as shown in FIG. 1i. These two waves applied to a gate G₃ result in a wave, shown in FIG. 1j, which includes a pulse following each transition in the input signal of FIG. 1a. The wave of FIG. 1j is applied to the synchronizing input of an oscillator including an "or" gate G₄, a delay unit D₄ and an amplifier A. The output of amplifier A is coupled back to a feedback input of "or" gate G₄.

Every pulse of the wave of FIG. 1j applied to "or" gate G₄ appears at output line 12 of the oscillator. Also, every pulse at output 12 is delayed in delay unit D₄, amplified in amplifier A and passed through "or" gate G₄ to appear again on output line 12. Once started, the oscillator continuously produces an output wave (FIG. 1k) having a period equal to one-half the duration of a bit cell of the input signal. The doubled frequency of the oscillator output insures that every pulse applied from gate G₃ to the oscillator acts as a synchronizing pulse to control the frequency of the oscillator.

The output 12 of the oscillator is coupled to the trigger input T of a triggerable flip-flop TF and is coupled to an input of a gate G₅. Flip-flop TF has a reset input R to which a reset pulse is applied prior to initiation of the message preamble for the purpose of insuring a correct phase of the flip-flop TF in response to oscillator pulses applied to its trigger input T. An output of flip-flop TF as shown in FIG. 1m has a frequency equal to one-half of the oscillator frequency. The half frequency output of the flip-flop TF is coupled to gate G₅ to pass every other one of the oscillator pulses to provide a wave as shown in FIG. 1n. The output of gate G₅ is delayed in delay unit D₅ to provide a "second" timing pulse wave

shown in FIG. 1p, and is further delayed in a delay unit D₆ to provide a "first" timing pulse wave shown in FIG. 1q.

Reference is now made to the lower portion of FIG. 2 for a description of the portion of the converter which converts the input information signal to an output information signal. The signal input terminal 10 is connected to an input of a gate G₆, and is connected through an inverter I₅ to an input of a gate G₇. These inputs to gates G₆ and G₇ are input and inverted input signal waves as shown in FIGS. 1a and 1b, respectively. These waves are repeated in the drawing following FIG. 1q for convenience in illustrating their effects on gates G₆ and G₇. Gates G₆ and G₇ also receive the first timing wave shown in FIG. 1q.

The output of gate G₆ is coupled to the set input S of a flip-flop F₁, and the output of gate G₇ is coupled to the reset input R of the flip-flop F₁. The corresponding outputs t and u from flip-flop F₁ are shown in FIGS. 1t and 1u, respectively. The outputs of flip-flop F₁ are delayed versions of the input and inverted input signals of FIGS. 1a and 1b. The amount of delay is equal to approximately half the duration of a bit cell of the input signal. The condition of the input signal of FIG. 1a at the time 20 of a pulse in the first timing wave of FIG. 1q is remembered in the flip-flop F₁ and is the same as the condition of the delayed input wave of FIG. 1t at the time 22 of the next following pulse of the second timing wave of FIG. 1p.

Gates G₈, G₉, G₁₀ and G₁₁ are all connected to be enabled by pulses of the second timing wave of FIG. 1p. 30 Gate G₈ is also connected to be enabled by the delayed, inverted input signal u from flip-flop F₁ and the input information signal a from input terminal 10. Gate G₉ is also connected to be enabled by the input information signal a and the delayed input information signal t from flip-flop F₁. Gate G₁₀ is also connected to be enabled by the delayed and inverted input signal u from flip-flop F₁ and the inverted input information signal b from inverted I₅. Gate G₁₁ is also enabled by an inverted input information signal b and a delayed input information signal t from flip-flop F₁.

The outputs of gates G₈ and G₁₁ are connected to the set input S of a second flip-flop F₂. The outputs of gates G₉ and G₁₀ are connected to the reset input R of flip-flop F₂. An output 30 from the flip-flop F₂ provides a simple non-return-to-zero signal, as shown in FIG. 1v, containing the information conveyed by the input information signal of FIG. 1a.

The second flip-flop F₂ is reset by an output from gate G₉ or G₁₀ at the time of a second timing wave pulse (FIG. 1p) if the input signal (FIGS. 1a and 1b) is then the same as the delayed input signal (FIGS. 1t and 1u). Of course, if the second flip-flop F₂ was previously reset, an additional resetting input has no effect on the output of the flip-flop. The second flip-flop F₂ is set from gates G₈ or G₁₁ at the time of a pulse of the second timing wave (FIG. 1q) if the input signal (FIGS. 1a and 1b) is then different from the conditions of the delayed input signal (FIGS. 1t and 1u). The result of the comparison of the input signal and the delayed input signal is to determine whether the input signal included a transition between the first and second halves of each input signal bit cell. If there is no difference between the input signal and the delayed input signal, the bit cell contained a "0" which is represented by a low output v at terminal 30 of the second flip-flop F₂. If there is a difference between the input signal and the delayed input signal, there was a transition in the input signal between the first and second halves of the input signal bit cell. Such a transition indicates a "1," which is represented by a high output v at terminal 30 70 of the second flip-flop.

The output 30 from the second flip-flop F₂ is a simple non-return-to-zero signal suitable for application to the signal input of a conventional shift register. The "first" timing wave (FIG. 1g) produced at the output of delay 75

unit D₆ is conveyed to clock output terminal 32 for application to the shift input of the shift register.

What is claimed is:

- 1: A code converter utilizing a self-clocking input information signal in which a transition occurs in the middle of a bit cell representing a "1" and a transition occurs between bit cells representing two successive "0's," comprising means to compare the first and second halves of each input signal bit cell and to provide a "same" output when they are the same, and a "different" output when they are different, and a flip-flop having one input coupled to receive said "same" output and having another input coupled to receive said "different" output, whereby the output of said flip-flop is a simple non-return-to-zero signal containing the information of said input signal.
2. A code converter utilizing a self-clocking input information signal in which a transition occurs in the middle of a bit cell representing a "1" and a transition occurs between bit cells representing two successive "0's," comprising means to translate said input signal to a delayed input signal delayed about one-half of a bit cell period relative to the input signal, means to compare the second half of each input signal bit cell with the delayed input signal then representing the first half of the respective input signal bit cell and to provide a "same" output when they are the same, and a "different" output when they are different, and a flip-flop having a reset input coupled to receive said "same" output and having a set input coupled to receive said "different" output, whereby the output of said flip-flop is a simple non-return-to-zero signal containing the information of said input signal.
3. A code converter utilizing a self-clocking input information signal in which a transition occurs in the middle of a bit cell representing a "1" and a transition occurs between bit cells representing two successive "0's," comprising means to extract from said input signal a timing wave having a pulse occurring during the second half of each input bit cell, means to translate said input signal to a delayed input signal delayed about one-half of a bit cell period relative to the input signal, means enabled by pulses of said timing wave to compare the second half of each input signal bit cell with the delayed input signal then representing the first half of the respective input signal bit cell and to provide a "same" output when they are the same, and a "different" output when they are different, and a flip-flop having one input coupled to receive said "same" output and having another input coupled to receive said "different" output, whereby the output of said flip-flop is a simple non-return-to-zero signal containing the information of said input signal.
4. A code converter utilizing a self-clocking input information signal in which a transition occurs in the middle of a bit cell representing a "1" and a transition occurs between bit cells representing two successive "0's," comprising means to extract from said input signal a first timing wave having pulses occurring during the first half of each input bit cell, and a second timing wave having pulses occurring during the second half of each input bit cell, a first flip-flop, first gate means enabled by pulses of said first timing wave and said input signal to set and reset said

first flip-flop and thereby produce a delayed input signal,
a second flip-flop, and
second gate means enabled by pulses of said second timing wave to set said second flip-flop when said input signal and delayed input signal are different, and to reset said second flip-flop when said input signal and delayed input signal are the same, whereby the output of said second flip-flop is a simple non-return-to-zero signal containing the information of said input signal.

5. A code converter utilizing a self-clocking input information signal in which a transition occurs in the middle of a bit cell representing a "1" and a transition occurs between bit cells representing two successive "0's," comprising

means including an oscillator synchronized by said input signal to generate a first timing wave having pulses occurring during the first half of each input bit cell, and a second timing wave having pulses occurring during the second half of each input bit cell,

a first flip-flop,

first gate means enabled by pulses of said first timing wave and said input signal to set and reset said first flip-flop and thereby produce a delayed input signal, a second flip-flop, and

second gate means enabled by pulses of said second timing wave to set said second flip-flop when said input signal and delayed input signal are different, and to reset said second flip-flop when said input signal and delayed input signal are the same, whereby the output of said second flip-flop is a simple non-return-to-zero signal containing the information of said input signal.

6. A code converter utilizing a self-clocking input in-

formation signal in which a transition occurs in the middle of a bit cell representing a "1" and a transition occurs between bit cells representing two successive "0's," comprising

an oscillator having a period equal to one-half the duration of said bit cells,

means responsive to each transition of said input signal to supply a synchronizing pulse to said oscillator,

means to derive from the output of said oscillator a first timing wave having pulses occurring during the first one-half of each input bit cell, and a second timing wave having pulses occurring during the second other half of each input bit cell, a first flip-flop,

first gate means enabled by pulses of said first timing wave and said input signal to set and reset said first flip-flop and thereby produce a delayed input signal, a second flip-flop, and

second gate means enabled by pulses of said second timing wave to set said second flip-flop when said input signal and delayed input signal are different, and to reset said second flip-flop when said input signal and delayed input signal are the same, whereby the output of said second flip-flop is a simple non-return-to-zero signal containing the information of said input signal.
